UNITED STATES PATENT OFFICE

2,653,067

TIGHTENING APPARATUS FOR
TYPEWRITER MOUNTINGS

John H. Page, Muskegon, Mich., assignor to
Shaw-Walker Company, Muskegon, Mich., a
corporation of Michigan

Application August 29, 1951, Serial No. 244,226

5 Claims. (Cl. 312—28)

1

This invention relates to improvements in locking devices especially adapted for counterbalanced typewriter platforms of the kind wherein in the platform with its typewriter can be removed from a retracted lowered position within a pedestal desk to an elevated writing position at the front of the desk.

More particularly, the invention relates to an improved locking device for holding the platform rigidly in writing position so as to eliminate objectionable instability often found in counterbalanced typewriter platforms of the kind above referred to.

A common form of counterbalancing mechanism now in commercial use includes a pair of inwardly opening hooks carried at each side of the typewriter platform, which hooks are moved into engagement with pins fixed on brackets on opposite sides of the pedestal compartment when the platform is in elevated writing position. Such devices usually have counterbalancing springs, and sometimes additional locking means, intended to hold the hooks seated against the pins to resist any movement or looseness of the platform while the typewriter is in use. In practice, however, such holding means are often insufficient for this purpose, or the parts become worn or get out of adjustment, so that the platform tends to wobble or vibrate when in its elevated writing position.

The principal object of the present invention is to provide a simple and efficient locking means, especially adapted for use in conjunction with or as an attachment to counterbalanced typewriter supports of the kind above referred to, wherein the operator may positively lock the retaining hooks against the retaining pins with a direct pull when the platform is in its extended elevated position.

Other objects and advantages of the invention will appear from time to time as the following description proceeds.

The invention may best be understood by reference to the accompanying drawings, in which:

Figure 1 is a plan view of the locking device as applied to a typewriter desk, with the top of the desk removed, and with parts thereof shown in section;

Figure 2 is a section taken on line 2—2 of Figure 1;

Figure 3 is a detail section taken on line 3—3 of Figure 1;

Figure 4 is a detail section taken on line 4—4 of Figure 1;

Figure 5 is a fragmentary perspective view of

2

one of the supporting plates fixed on the inner sides of the desk.

Referring now to the embodiment of the invention illustrated in the drawings, my improved locking device is shown as applied to a commercial form of counterbalanced typewriter platform mechanism, in which a typewriter platform 10 is adapted to be swung from a retracted position within a compartment 11 of a pedestal desk, indicated generally at 12, into an elevated typewriting position, as shown in Figure 2.

The form of counterbalancing mechanism chosen herein to illustrate the use and operation of my locking device is substantially the same as disclosed in Patent No. 2,245,526, issued June 10, 1941, and including a pair of metal brackets 15 which are connected to opposite sides of a transverse plate 16 at the rear end of the platform 10. Said brackets are provided with upwardly extending arms 17 having forwardly opened notches or hooks 18 adapted to engage a pair of studs 19 on side plates 20 which are fixed just within the front of the compartment 11 below the desk top 21. Further details of construction of the counterbalancing mechanism need not be described in detail herein, as they form no part of the present invention and are fully described in the patent previously mentioned, excepting to point out that, when the platform 10 is in its elevated position for normal operation of a typewriter thereon, as shown in Figure 1, the hooks 18 are in engagement with the studs 19, and the associated linkage and counterbalancing springs are intended to hold the hooks in engagement with said studs.

Certain modifications of counterbalancing mechanisms of the kind disclosed in the above patent have also been used, including latching devices in the linkage system for holding the platform in its typewriting position, such as that disclosed in Patent Number 2,245,256, issued June 10, 1941, but such latching devices require that the outer end of the platform be raised by hand to release the latch. In any event, such latching devices are disposed in the linkage system quite remote from the securing hooks 18 and their cooperating studs 19, so that there is no positive direct locking means to assure proper rigidity of the platform in its typewriting position.

Referring now to the novel form of locking mechanism which constitutes the subject matter of the present invention, I provide an elongated base plate 25 which is seated on the transverse plate 16 of platform 10, slightly below the level of the main upper supporting surface 26 of said

platform. Said base plate is attached to the transverse plate 16 by a plurality of bolts 21, 21 extending through longitudinally elongated slots 28, 28 in the base plate so as to permit sliding adjustment of the base plate longitudinally of the platform 10. The base plate 25 has upwardly extending flanges 29, 29 along opposite sides thereof which form guide members for a somewhat shorter sliding plate 30. The latter plate is of generally inverted U-shape in cross section, with a top wall 31, side walls 32 slidably engaging the outer faces of the base plate flanges 29, and with outwardly extending flanges 33, 33 at the lower ends of the side walls 32.

A locking lever 35 has its inner end pivoted at 36 to the extreme inner end of the base plate 25. Said lever has an upwardly offset main portion 37 extending forwardly and horizontally in spaced relation above the upper surface of the sliding plate 30, with its free forward end extending beyond the front face of the compartment when the platform is in its elevated position, as shown in Figure 1. In the form shown herein, the forward end of the lever 35 has a control knob 38 disposed above the typewriter supporting surface 26 of the platform 10.

A cam supporting plate, indicated generally at 39, is suitably fixed as by welding to the under face of the operating lever 35. Said cam supporting plate has a channel member 40 secured as by welding to its under face. Said channel member has a pair of opposed downwardly extending flanges 41, 41 which form a horizontally disposed cam-like groove for receiving a guide roller 43 rotatably mounted on a stud 44 fixed to the top wall 31 of the sliding plate 30. The channel member 40 has a portion 45 disposed generally tangentially to the pivotal axis of the operating lever 35. Said channel member is then continued with an outer portion 46 disposed at a forward oblique angle to the channel portion 45 and at an angle of substantially less than 90 degrees to the longitudinal axis of the handle 35, as shown in Figure 1.

A pair of locking bars 50, 50 are pivotally connected at their inner ends to the laterally extending flanges 33, 33 of the sliding plate 30. The outer ends of these locking bars pass through arched brackets 51, 51 which as shown herein are mounted on inturned flanges 15a, 15a of the bracket 15, 15 at the opposite side edges of the platform. The locking bars 50, 50 have their rear edges formed with outwardly tapered cam surfaces 52, 52 at the outer ends thereof. The arched brackets 51 are of sufficient width to permit limited rocking movement of the outer ends of the locking bars therein as said bars are moved from their forward unlocked position shown in dotted lines in Figure 1, to their rearward fully locked position shown in full lines in the same figure. During the rocking movement and while in locked position, the locking bars fulcrum against the rear faces of the brackets 51.

The extreme outer ends of the locking bars 50, 50 are adapted to project into locking engagement with suitable abutments carried on the side plates 20, 20 which carry the studs 19, 19 and are fixed within the front of the compartment 11, as previously described. In the form shown herein, the locking abutments consist of elongated slots 55, 55 in said side plates, in which the extreme ends of the locking bars 50, 50 are adapted to be inserted. Said slots are disposed in longitudinal alignment between the studs 19 so that

the latter studs will be forced within the hooks 18, and firmly retained therein, when the locking bars 50 are moved to their fully extended locking position as shown in full lines in Figure 1.

The use and operation of the device may now be described as follows:

The locking device is intended for actuation after the platform 10 has been swung into its elevated typewriting position as shown in Figure 2, with the hooks 18 in supporting engagement with the studs 19.

Figure 1 shows in dotted lines the outer ends of the locking bars 50, 50 in their fully retracted unlocked position, and in full lines their extended locked position, respectively. The operating lever 35 extends beyond the front face of the compartment in position to be actuated by the user. The channel 42 carried on the under face of the operating lever 35 has a portion 46 disposed at an oblique angle to the lever 35 so that, when the lever is swung in one direction, the guide roller 43 on the sliding plate 30 has a cam-like movement along the channel 42, causing the sliding plate to move inwardly and project the outer ends of the locking bars 50, 50 through the brackets 51 into locking engagement within the elongated slots 55, 55 in the side plates 20, 20. When the lever is moved in the opposite direction, the movement of the locking bars 50, 50 is reversed. The cam surfaces 52, 52 along the rear edges of the locking bars have both sliding and rocking movement while fulcrumed against the rear faces of the arched brackets 51, 51 fixed on the platform, when the inner ends of the locking bars are moved laterally toward their locking position.

It will be observed that, due to the simultaneous rocking and endwise sliding movement of the outer ends of the locking bars while fulcrumed within the brackets 51 during the locking movement, the outer ends of said locking bars are first moved rearwardly as they enter the slots 55, 55 and are then swung forwardly into engagement with the front ends of said slots so as to take up any slack or looseness which might be present between the open hooks 18 and their cooperating studs 19, and hold them firmly in engagement with each other.

The inner, generally tangential portion 45 of the guide channel 42 is arranged to permit slight arcuate movement of the rocking lever after it has reached its fully locked position, and yet retaining the parts in said locked position until positively released by reverse movement of the locking lever.

The proper final position of the outer ends of the locking arms 50 can be adjusted by loosening the bolts 27, 27 which secure the base plate 25 to the transverse plates 16 of platform 10 and then tightening the bolts in the proper readjusted position wherein the pins 19 will be seated firmly within the hooks 18 when the rocking lever 35 is swung to its fully locked position.

Although I have shown and described a certain embodiment of my invention, it will be understood that I do not wish to be limited to the exact construction shown and described, but that various changes and modifications may be made without departing from the spirit and scope of the invention as defined in the appended claims.

I claim:

1. In a locking device for a supporting platform movable endwise into extended position relative to a fixed base and including a plurality of inwardly facing open hooks at opposite sides

of said platform engageable with studs fixed on the base, the combination of a guide support slidably mounted centrally of the platform at its inner end, a pair of locking arms pivotally connected to opposite sides of said guide support, guide means for the outer ends of said locking arms fixed at opposite sides of said platform permitting simultaneous sliding lateral extension and rocking movement of said arms with the latter fulcrumed within said guide means, the outer ends of said locking arms being adapted for engagement with abutments on the fixed base when said locking arms are moved to extended position, a control lever pivotally mounted adjacent the inner end of said platform and having a free end extending into position for manual operation beyond said base when said platform is in extended position with respect to said base, said control lever having a cam member thereon, and a guide member carried on said guide support in engagement with said cam member to move the outer ends of said locking arms into locking engagement with said abutment means in a direction opposed to that in which said hooks are moved into engagement with said studs.

2. A locking device in accordance with claim 1, wherein the edges of said locking arms at their outer ends have tapered cam surfaces opposite the edges which have locking engagement with the abutments on the fixed base to afford rocking and sliding engagement of said cam surfaces relative to the guide means on opposite sides of the platform, and cause the abutment engaging edges of said arms to be swung forwardly toward the abutments progressively with the lateral extension of said arms.

3. In a locking device in accordance with claim

1, wherein the cam member on the control lever consists of a guide channel having an end portion disposed generally tangential to the pivot of said lever, to permit limited movement of said lever in its fully locked position, while retaining the parts in locked position.

4. In a locking device in accordance with claim 1, wherein the slidable guide support is movably mounted on an elongated plate which is mounted for longitudinal adjustment on the platform, said control lever being pivotally mounted on said elongated plate so that the locking tension of the locking arms is controlled relative to their abutments when in fully locked position.

5. The structure of claim 1, wherein said control lever is adapted to be manually operated from the upper surface of the movable platform and adjacent, but spaced from, the fixed base.

JOHN H. PAGE.
